(57) CLAIM

The ornamental design for an open back bra, as shown and described.

DESCRIPTION

FIG. 1 is a front, left, top perspective view of a first embodiment of an open back bra showing my new design; FIG. 2 is a rear, right, bottom perspective view thereof; FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, left, top perspective view of a second embodiment of an open back bra;

FIG. 10 is a rear, right, bottom perspective view thereof;

FIG. 11 is a front view thereof;

FIG. 12 is a rear view thereof;

FIG. 13 is a left side view thereof;

FIG. 14 is a right side view thereof;

FIG. 15 is a top plan view thereof; and,

FIG. 16 is a bottom plan view thereof.

The broken lines are representing stitching of the open back bra and the broken lines form no part of the claimed design.

1 Claim, 16 Drawing Sheets
